Primary Examiner — Marianne Pandozzi(74) *Attorney, Agent, or Firm* — Alston & Bird LLP(57) **CLAIM**

I claim the ornamental design for coffee machine, as shown and described.

DESCRIPTION

FIG. 1 is a perspective view of coffee machine showing my new design;

FIG. 2 is a front elevation view thereof;

FIG. 3 is a right side elevation view thereof;

FIG. 4 is a left side elevation view thereof;

FIG. 5 is a top plan view thereof; and,

FIG. 6 is a rear elevation view thereof.

The broken lines are directed to unclaimed features. The broken lines form no part of the claimed design.

1 Claim, 3 Drawing Sheets(56)
